UNITED STATES PATENT OFFICE.

CLAYTON J. GOEBEL AND CARL BARTELS, OF HAMILTON, OHIO, ASSIGNEES TO THE MOSLER SAFE COMPANY, OF HAMILTON, OHIO, A CORPORATION OF NEW YORK.

ENTRANCE PLATFORM FOR VAULTS AND THE LIKE.

Application filed June 3, 1925. Serial No. 34,586.

This invention relates to entrance platforms for vaults and the like, and more particularly relates to platforms adapted to be raised into position level with the entrance into the vault and the banking floor, and to be lowered from this position to permit the vault door to be opened and closed.

One of the principal objects of our invention is to provide an improved entrance platform of the above-mentioned character; one which is semi-automatic in operation, and at the same time does not require supplementary power devices, such as levers, 10 motors, etc., for the purpose. More specifically, this object of our invention is to provide a platform of the character described which requires a minimum amount of force, and preferably the mere application of a person's weight, to cause the platform to move into one position, and does not require the application of any exterior power to cause it to move into another position.

Another object of our invention is to provide a platform of the character referred to, which in part serves as a door stop to prevent the door from swinging, thus eliminating the need of any supplementary door stop, which is unsightly in a banking 20 room.

Other objects of our invention will be in part obvious and in part pointed out hereinafter.

In accordance with our invention, the platform comprises a main portion and a smaller door portion alongside of the main portion. The platform portions are so connected and counterbalanced that the weight 30 of a person placed on the main platform will carry both platforms into lowered position, and when this weight is removed, both portions will rise automatically, but the main portion may rise above the small portion when the small portion is checked by the door. Means are provided for releasably locking the platform in either of its two extreme positions, and means, accessible for operation, are provided for releasing the locking means. The releasing 40 means preferably include a manually operable plunger adjacent the platform.

In order that a clearer understanding of our invention may be had, attention is here- 50 by directed to the accompanying drawings,

forming a part of this application and illustrating one possible embodiment of our invention.

Referring to the drawings:

Fig. 1 is a top plan view of a platform embodying our invention, associated with a door portion of a vault, the door being closed and the adjacent vault walls being shown in section;

Fig. 2 is a view similar to Fig. 1, except that the vault door is shown open, and a supplementary bridge is shown extending across the door jamb;

Fig. 3 is a front view, partly in section, of the platform and its elevating mechanism, the view being taken substantially on the line 3-3 of Fig. 4;

Fig. 4 is a top view of the elevating mechanism, and is taken substantially on the line 4-4 of Fig. 3;

Fig. 5 is a horizontal sectional view, and is taken substantially on the line 5-5 of Fig. 3;

Fig. 6 is a top view of the lock releasing mechanism with the cover plate removed, and is taken substantially on the line 6-6 of Fig. 7;

Fig. 7 is a vertical sectional view of the same, showing the platform locked in raised position and showing in dotted lines the platform in lowered position and released, this view being taken on the line 7-7 of Fig. 8;

Fig. 8 is a sectional view of the same, and is taken on the line 8-8 of Fig. 7;

Fig. 9 is a sectional view of a detail of the construction, and is taken on the line 9-9 of Fig. 4;

Fig. 10 is a sectional view of a detail of the construction, and is taken on the line 10-10 of Fig. 4;

Fig. 11 is a sectional view of a detail of the construction, and is taken on the line 11-11 of Fig. 4;

Fig. 12 is a sectional view of a detail of the construction, and is taken on the line 12-12 of Fig. 4;

Fig. 13 is a sectional view of a fragment of the construction, and is taken on the line 13-13 of Fig. 4;

Figs. 14 and 15 are each sectional views, and are taken respectively on the lines 14-14 and 15-15 of Fig. 5;

Fig. 16 is a similar sectional view, but shows the platform in lowered position; and

Figs. 17 and 18 are each sectional views of fragments of the construction, and are taken respectively on the lines 17—17 and 18—18 of Fig. 5.

5 Similar reference characters refer to similar parts throughout the several views of the drawings.

Referring to the drawings, for purposes of illustration, there is shown a wall 1 of a 10 vault, having a doorway 2 and a door 3 supported on the wall by means of hinge mechanism 4 of the crane type. The vault doorway has a raised sill 5, and the usual stepped jamb. The main floor level outside of the 15 vault is designated 6, and this is usually level with the vault sill 5. The main floor 6 is cut away appropriately to permit the door 3 to swing open and closed, and is preferably faced with a metal plate 7 to provide 20 a finished curb. The platform embodying our invention occupies this cut-away portion of the main floor, and in the present instance is shown to be somewhat semi-circular in form. The platform comprises two parts 25 or sections, one of which, 8, is shaped to be at least the size of the door in its vertical projection and is so located that it will be beneath the door in line therewith when the door is fully opened. The other and larger 30 part 9 of the platform is alongside of the portion 8.

Beneath the platform and upon a suitable 35 foundation, such as 10, is placed suitable supporting structure for the platform raising and lowering mechanism, which is individual to each platform section. Such supporting structure may comprise suitably located I-beams 11, which, if desired, may be secured to each other and to the curb plate 40 7, above mentioned, by suitable angle irons 12, or by other means.

Each of the platform portions 8 and 9 may 45 comprise suitable flooring secured on channel irons 13, to which the raising and lowering mechanism is connected.

The raising and lowering mechanism is 50 similar for each of the platform portions, although individual to each. For the portion 9, the mechanism includes a plurality of vertical racks 14, which are rigidly secured at their tops to the channel members 13. These racks are in constant mesh with pinions 15. In constant mesh with each pinion on the opposite side is another rack member 55 16, which extends upwardly from a pan 17 and is rigidly secured thereto. The pinions 15 are keyed or otherwise secured to suitable shafts 18, which are mounted in anti-friction bearings 19, these bearings being carried on blocks 20, which rest on and 60 are secured to the tops of the I-beams 11 by suitable screws 21, or by other means. As shown most clearly in Fig. 5, this platform portion is supported on four rack members 65 14 arranged in a rectangle, and the counter-

poise pan 17 is suspended from four racks 16 arranged in corresponding rectangular relation. There are three shafts 18 arranged on three sides of this rectangle, and the adjacent ends of the shafts carry intermeshing 70 bevel gears 22, whereby the racks are connected for synchronized movement and the platform portion is maintained level at all times. The racks 14 at their upper ends may be threaded into suitable blocks 23, 75 which are welded or otherwise secured to plates 13', which in turn are secured to the channel irons 13. To avoid the possibility of racks 14 coming out of mesh with the pinions 15, each block 20 may be provided 80 with a projecting arm 24, which carries a roller 25 in position directly behind the adjacent rack 14. These rollers prevent the racks from becoming disengaged from the pinions. The counterbalance pan 17, as 85 shown, may consist of four channel irons 26 arranged into a rectangle and secured together at their meeting edges by means of angle plates 27 and having a plate 28, constituting a bottom, welded or otherwise secured to the lower flanges of these channel members. Preferably, bumpers 29 are provided on the bottom of the pan, and other bumpers 30 are provided on the tops of the 90 racks 16. The bumpers 29 take the shock 95 when the counterbalance pan reaches the foundation, and the bumpers 30 take the shock when the racks 16 meet the descending flooring of the platform.

The pan 17 is weighted so as to be not 100 quite as heavy as the parts counterbalanced thereby. Scrap iron or concrete may be used to give the proper counterbalance effect, or other means may be provided. Preferably the weights of the platform and counterpoise are so arranged as to normally cause the platform to assume and remain in raised position, and so that a person's weight placed on the platform will cause it to lower and cause the counterpoise to rise.

For the smaller platform portion 8 the raising and lowering mechanism, as shown, includes racks 14' and 16', pinions 15', bearings 19', weighted counterpoise pan 17', shafts 18', having meshing bevel gears 22', 115 blocks 20', arms 24', rollers 25', pan channels 26', and bumpers 29' and 30', all similar to the corresponding parts for platform portion 9, and similarly arranged.

To prevent the platform from lowering, 120 at undesired times, under the weight of a person, we provide means for releasably locking the platform in raised position, and provide means for holding the platform releasably in lowered position to permit the 125 door to be opened and closed. There also are manually operable means for releasing these locking means to permit the platform to move into raised or lowered position. These latter means, as shown, may comprise 130

a vertically reciprocable plunger 31 disposed in the banking room floor 6 adjacent the platform. A spring 32 normally holds the plunger 31 in raised position. An inclined link 33 is pivotally connected to plunger 31 and to a horizontally reciprocable member 34, which, as shown, is T-shaped. Member 34 has an upper releasing lug 35 and a lower releasing lug 36, each positioned to move through an aligned perforation 37 or 38 in the adjacent curb wall 7. A bolt or detent 39 is slidably maintained beneath the flooring of the platform and is constantly urged outward by means of a spring 40. This bolt is positioned to project into hole or keeper recess 37 when the platform is in raised position, thus preventing the platform from lowering, and is positioned to engage in the hole or keeper recess 38 when the platform is in lowered position, thus preventing the platform from rising. Preferably, the end of the bolt 39 is provided with a roller 41 to provide for the easy disengagement of the bolt by the releasing member 34 when the plunger 31 is depressed, and to permit the bolt to move easily along the curb 7 from one hole to the other as the platform rises or lowers. In Fig. 7 there is shown in full lines the position of the detent when in locking position, and in the same figure there is shown in dotted lines the position of the detent when moved into unlocking position in consequence of the depression of plunger 31.

Preferably, the platform carries a plurality of other bolts 39' distributed at various places on its edges, adapted to lock in suitable recesses formed at appropriate places in the curb plate 7. Preferably all these bolts are connected with each other to operate in unison under the influence of the spring 40 and the releasing mechanism heretofore described. To accomplish this, these bolts may be connected by suitable link and lever arrangement supported from the bottom of the platform section 9. For instance, there may be a disc 42 rotatably mounted on a stud 43, and each bolt 39 may be connected to this disc by means of a link 44 in such a way that retraction of one bolt causes such rotation of the disc 42 that all the other bolts will be retracted, and that the movement of one bolt into locking engagement with one of its holes in the curb 7 will cause all the other bolts to engage in their corresponding holes in the curb. As shown, two of the bolts are arranged to engage the small platform section, whereby the small platform section is restrained against moving with respect to the larger portion until these bolts have been released. A rocking lever 44' is interposed where a reverse movement between a bolt 39 and a link 44 is required.

Various views of the drawings are specific to various structural details of the construc-

tion. These will now be referred to more fully.

Fig. 9 is a sectional view of the edge of the platform adjacent the vault. This view shows the platform section 9, to which is secured the housing 45, in which the bolt 39 slides. A vertical strip 46 is secured along this edge of the platform, and to the outer face of this strip is secured an angle bracket 47, and a horizontal metal plate 48 seated thereon. Plate 48 extends to the vault door and is cut away for the hinge thereon. Above this plate and bracket is a block 49, on which the outer edge of the floor bridge 50 may be supported when the door is open and the platform raised.

As shown in Fig. 10, the floor material 8' may be secured on the smaller platform portion by means of under-cut retaining members 51, which are secured to the beams 13 by means of screws 52. This permits the flooring 8' to be removed, so that access may be had to the elevating mechanism below, when desired. The flooring may be reinforced by means of a flat metal plate 53.

Fig. 11 shows an angle member 54 secured to a depending marginal plate 55 on the edge of the small floor portion 8, with the bracket 54 having a horizontal flange 56 seated beneath a marginal depending strip 57 on the adjacent edge of the main platform portion 9. When the main platform lowers, the engagement of members 56 and 57 carries the smaller platform portion downward, but permits the larger platform portion to rise independently of the smaller portion, as when the portion 8 is checked by the open vault door.

Fig. 12 shows the edge of the platform portions adjacent the curb 7. Here the periphery of the platform carries a depending plate 58. The members 7 and 58 may be curved on their upper edges with bronze, as at 59, to create an attractive appearance. The flooring of the main platform may include a metallic plate 53, to the edges of which the strip 58 may be welded, as at 61. Any suitable flooring material, 62, may be placed on the plate 53.

Referring to Fig. 13, the plate 58 may also be secured to the plate 60 by means of angle members 63, which abut and are secured to both these members. The curb plate 7 may be supported in place by means of angle members 64, which have one leg abutting and secured to the curb 7 and having the other leg extending into recesses in the banking floor 6, these recesses being filled with concrete 65 to anchor the members 64 in place. Concrete may also be used to fill any space which may exist between the curb 7 and the bank floor 6, as at 66.

The operation is as follows: When the vault is closed, both platform portions are usually in raised positions. When it is de-

sired to open the vault, the operator depresses the plunger 31 with one foot and places the other foot on the top of the platform with a sufficient amount of weight 5 to start the counterbalanced platform in its descent. Such descent is possible for the reason that the act of depressing the plunger 31 moves the slide 34 toward the platform, so as to push the end of detent 39 from the 10 hole 37, and this movement of the detent 39, through its connection with the disc 42, causes all the other detents to be released. When downward movement of the platform has begun, as before stated, the operator 15 preferably releases the plunger 31, and allows his weight to carry the platform to its lowest point. At this point the spring 40 causes the bolt 39 to lock in the lower recess 38, and through its connection with 20 disc 42 causes all the other bolts to lock in corresponding recesses in the curb 7. This downward movement of the main platform portion carries with it the smaller platform portion by reason of the engagement of 25 members 54 and 57, as heretofore described. The door is now swung open. The operator then depresses the plunger 31 without placing any weight on the platform. This releases the bolts from the lower recesses and 30 permits the counterpoise weight to raise the main platform portion to its uppermost position. The operator may release the plunger either during or after the ascent of the platform. Spring 40 now causes bolt 39 to lock in 35 the upper recess 37, and the other bolts will also lock in the corresponding recesses in the curb. The smaller platform portion, however, will not rise to its full extent by reason of the door being thereabove and preventing 40 such movement, and this smaller platform portion will lock against the door and will thus act as a door check to prevent the door from being closed until this smaller platform portion has again been lowered. 45 In order to lower this small platform portion, to permit closing of the door, it will be necessary for the operator to lower the main platform portion to full extent. During the descent of the main platform portion, 50 its flange 57 will engage the flange 56 on the smaller platform and carry the smaller platform down to its lowest limit, and both platform portions will be locked automatically in this position until the bolts 39 are 55 released by actuation of the plunger 31. The door is closed while both platform portions are in the lowest position. Then, if the operator depresses the plunger 31 without placing his weight on the platform, both platform 60 portions will be raised to the banking floor level automatically in consequence of being overbalanced by the respective counterpoise devices 17 and 17'.

After opening the door and raising the 65 main platform portion, the floor bridge 50

is put into place, and before lowering the platform to close the door, this member is removed.

As many changes could be made in the above construction, and as many different 70 embodiments of this invention could be made without departing from the scope thereof, it is intended that all matter contained in the above description or shown in the accompanying drawings shall be interpreted as illustrative and not in a limiting 75 sense.

It is also to be noticed that a platform of the above construction may conveniently be shipped and installed as a unit, and in this 80 event the curb plate 7 is preferably secured to the beams 11 at the factory or assembling plant, to tie the entire assembly firmly together.

What we claim is:

1. In a device of the character described, in combination, pinions, a platform having depending racks in constant mesh with one side of said pinions, and a counterpoise including upwardly extending racks in constant mesh with the opposite sides of said pinions, whereby said platform and counterpoise are supported by said pinions for simultaneous counterbalanced movement in opposite directions. 95

2. In a device of the character described, in combination, pinions, a platform having depending racks in constant mesh with one side of said pinions, and a counterpoise including upwardly extending racks in constant mesh with the opposite sides of said pinions, whereby said platform and counterpoise are supported by said pinions for simultaneous counterbalanced movement in opposite directions, the counterbalance effect being such that the weight of a person placed on the platform lowers the platform and raises the counterpoise, and when this weight is removed, the platform rises and the counterpoise lowers. 100

3. In a device of the character described, in combination, pinions, a platform having depending racks in constant mesh with one of said pinions, a counterpoise including upwardly extending racks in constant mesh with the opposite sides of said pinions, whereby said platform and counterpoise are supported by said pinions for simultaneous counterbalanced movement in opposite directions, the counterbalance effect being such that the weight of a person placed on the platform lowers the platform and raises the counterpoise, and when this weight is removed, the platform rises and the counterpoise lowers, and means operable 115 from adjacent the platform for releasably locking the platform in raised and lowered 120 positions. 125

4. In a device of the character described, in combination, a platform including two 130

portions side by side, each counterbalanced to move automatically into raised position, and to move into lowered position when downward pressure is applied thereto.

5. In a device of the character described, in combination, a platform including two portions side by side, each counterbalanced to move automatically into raised position, and to move into lowered position when downward pressure is applied thereto, said platform portions having interlocking parts whereby one of said portions may rise independently of the other portion and whereby said other portion is carried down when said 15 independently rising portion lowers.

6. In a device of the character described, in combination, a plurality of revolvable shafts, pinions keyed to said shafts, a platform, racks depending from said platform 20 meshing with one side of said pinions, a counterpoise, racks extending upwardly from said counterpoise meshing with the opposite side of said pinions, whereby said platform and device tend to counterbalance 25 each other.

7. In a device of the character described, in combination, a plurality of revolvable shafts, pinions keyed to said shafts, a platform, racks depending from said platform 30 meshing with one side of said pinions, a counterpoise, racks extending upwardly from said counterpoise meshing with the opposite side of said pinions, whereby said platform and device tend to counterbalance each other, 35 said shafts being connected to revolve in unison, whereby the racks and pinions have identical movement, and the platform is maintained level at all times.

8. In a device of the character described, 40 in combination, a stationary curb having upper and lower keeper recesses, a platform adjacent the curb and carrying a detent, said platform being movable vertically to position the detent opposite said curb recesses, 45 means for projecting said detent into a recess as it comes opposite thereto, to lock the platform against movement with respect to

the curb, manually operable means for disengaging the detent from each recess, and means for moving the platform. 50

9. In a device of the character described, in combination, a stationary curb having upper and lower keeper recesses, a platform adjacent the curb and carrying a plurality of detents, said platform being movable 55 vertically to position the detents opposite said curb recesses, means for projecting said detents into recesses as the detents come opposite thereto, to lock the platform against movement with respect to the curb, manually operable means for disengaging all 60 the detents simultaneously from the recesses, and means for moving the platform.

10. In a device of the character described, in combination, two vertically movable platform portions side by side, a movable detent on one of said portions, a recess for the detent on the other portion, means for projecting the detent into said recess when aligned therewith, to lock said two platform portions together against independent movement, means for disengaging the detent from the recess to permit independent movement of said platform portions, and means for moving said platform portions. 75

11. In a device of the character described, in combination, two vertically movable platform portions side by side, a movable detent on one of said portions, a recess for the detent on the other portion, means for projecting the detent into said recess when aligned therewith, to lock said two platform portions together against independent movement, means for disengaging the detent from the recess to permit independent movement 80 of said platform portions, and means for moving said platform portions, an edge part of one of said platform portions being above and in the vertical projection of an edge of the other platform portion. 85 90

This specification signed this 13 day of May, 1925.

CLAYTON J. GOEBEL.
CARL BARTELS.

Certificate of Correction.

It is hereby certified that in Letters Patent No. 1,601,823, granted October 5, 1926, upon the application of Clayton J. Goebel and Carl Bartels, of Hamilton, Ohio, for an improvement in "Entrance Platforms for Vaults and the Like," errors appear in the printed specification requiring correction as follows: Page 4, line 113, claim 3, after the word "one" insert the word *side*; page 5, line 89, claim 11, after the word "edge" insert the word *part*; and that the said Letters Patent should be read with these corrections therein that the same may conform to the record of the case in the Patent Office.

Signed and sealed this 2d day of November, A. D. 1926.

[SEAL.]

WM. A. KINNAN,
Acting Commissioner of Patents.
